UNITED STATES PATENT OFFICE.

HARRY S. VINCENT, OF RIDGEWOOD, NEW JERSEY, ASSIGNOR TO FRANKLIN RAIL-WAY SUPPLY COMPANY, A CORPORATION OF DELAWARE.

DRIVING BOX.

Application filed April 3, 1922, Serial No. 548,938. Renewed May 20, 1927.

My invention relates to vehicle journal boxes especially suitable for the drive wheels of locomotives. The invention affords a new box construction which is simple and rugged, and of moderate cost to manufacture; is convenient, durable, and effective in use, and affords unusually good bearing for taking horizontal thrusts like the piston thrust, for example; is easy to remove or take apart for repairs; and is free from serious drawbacks and defects of boxes at present used on locomotives.

In journal boxes now used on locomotives, the box has the form of an inverted U straddling the driver shaft or journal, and carries the locomotive weight on its transverse upper member. The box is mounted and engaged to move up and down in vertical pedestal jaws in the locomotive frame,—the lower ends of the jaws being closed by a removable part termed the "frame pedestal binder." The bearing surface in contact with the driver shaft is formed by a crown bearing piece (usually of brass or the like) originally separate, but secured in the box by forcing it thereinto under heavy pressure,—so as to make it, in effect, one part with the rest of the box until removed by a corresponding exertion of force. The face of the box adjacent the drive wheel hub has a bearing surface for taking the lateral or "end" thrust of this wheel,—though this bearing area is necessarily small, because of the construction. Between the lower ends of the side members of the box is mounted a lubricator device or "cellar" for supplying lubricant to the lower side of the rotating driver axle or shaft,—which device is removable for replenishment or cleaning at short intervals.

For reasons which it is unnecessary to discuss, it is found that in service the side members of the box are forced together and "pinch" in, which tends to jam or bind the lubricator, and is productive of other objectionable results. Both the initial insertion of the bearing crown piece and its removal and replacement as required from time to time result in distortion and weakening of the box, and so tend to shorten its useful life. Being essentially one single member that must be removed from time to time, the unitary box and crown structure can only make contact with the upper half of the axle, so that there cannot be any bearing

surface below the center of the axle to help take horizontal thrusts. Moreover, either renewal of the crown piece or relining of the hub face of the box from time to time entails removing the entire box from the locomotive frame; and this, in turn, entails either dropping the drivers, or some other tedious and laborious operation of analogous character.

My present invention not only obviates deformation of the journal box in service and consequent lubricator trouble, but also permits easy, quick removal of the box without dropping the wheels. It makes possible ample lateral bearing surface at the axle for taking horizontal thrusts from the piston, for example, and allows the crown bearing itself to be made independently removable for repair or replacement, without any necessity for removing the box as a whole.

How these and other advantages can be obtained in connection with my invention will appear from my description hereinafter of the best embodiment of the invention at present known to me.

In the drawings, Fig. 1 is a partial side elevation and section showing a journal box embodying my invention in place in the pedestal of a locomotive frame,—the view being taken, it will be understood, from the inner side of the box.

Fig. 2 is a plan view of the journal box with its right-hand portion broken away and in section about as indicated by the line 2—2 in Fig. 1.

Fig. 3 shows a vertical mid section through the journal box, taken as indicated by the line 3—3 in Fig. 1.

Fig. 4 is a partial side elevation and section similar to Fig. 1 showing a somewhat different construction,—details relating to the lubricating arrangements being omitted.

Fig. 5 is a corresponding fragmentary plan view.

The box shown in the drawings comprises a box structure 10 having at its sides or limbs 11 and 12 the usual flanges 13, providing grooves. The pedestal jaws 14 of the locomotive frame engage in these grooves and serve as guideways for up and down movement of the whole journal box.

The box structure 10 here shown is of a general yoke or U shape; but instead of being inverted (as in the prior constructions above referred to), the U is arranged erect

about the axle 15, with the transverse member 16 a short distance beneath the axle. The structure 10 is supported by being suspended (as it were) from the separate crown bearing structure, which in the present instance comprises an upper bearing part or member 17 resting on the axle 15 between the side members 11, 12, and also separate bearing parts or members 18, 18 at opposite sides of the axle extending substantially above and below its center, against the box sides. A bottomless sheet metal lubricator device or cellar 20 (shown as of the general Elvin type) is arranged in the box structure 10 beneath the axle 15, and its follower plate is urged upward toward the axle by a spiral compression spring 22 beneath it that is housed in a recess 23 in the member 16. The sides and the bottom of the box 10 are cut away or recessed to form transverse ridges or ways 24, 25 adjacent the top and the bottom of the lubricator or cellar 20: these ridges keep the cellar 20 in a definite position, yet offer little frictional resistance to its withdrawal at the open inner end of the box. At one end, the follower plate has a downward projecting indicator rod 26 that normally lies in a vertical slot in the transverse member 16. The cellar 20 may be secured in place by means of a horizontal retainer bar or rod 27 extending through engagement means in the form of apertured lugs 28, 28 on the members 11, 12 across the yoke opening at the inner end of the box 10, and itself secured in place by one or more keys 29.

Shoulders 30 extend inward from either side 11, 12 of the box structure 10 at its upper end, and the bearing member 17 has corresponding shoulders 31 which cooperate with the shoulders 30 in the support of the box structure 10 by the member 17. The member 17 is of such general width as to fit (snugly but not tightly) between the sides 11, 12 below the shoulders 30, while its upper portion is of such reduced width as to fit (snugly but not tightly) in the opening between the shoulders 30: i. e., the bearing corresponds substantially to the internal width of the box 10. At the upper and lower ends or edges of each member 18 are central upward and downward projecting lugs 32 adapted to engage and fit snugly in recesses 33 in the lower end of the upper member 17, on either side, and in recesses 34 in the ridges 24 on the corresponding side members 11 and 12. As shown, the upper and lower lugs 32 lie behind shoulders on the member 17 and behind the upper edges of the cellar 20, respectively. By virtue of the lugs and recesses 32, 33, 34 and of the frictional engagement of the parts, the bearing members 17 and 18 cooperate to prevent movement or displacement of any of them in the box structure 10, lengthwise of the axle

15 or otherwise. The space beside the lugs 32 in the recesses 33 and 34 is sufficient to permit ample independent lateral adjustment of the members 18 relative to the box sides 11, 12, either to secure initial snugness or to take up wear; and changeable shims or liners 34^x interposed between the members 18 and the box sides afford a convenient means of fixing or varying the adjustment.

Removable tapering pin or key members 35 engaged between the shoulders 30 and 31 normally wedge the members 17 and 18 fast in the box structure 10, maintaining the lower ends or edges of the member 17 firmly seated against shoulders formed by the upper edges of the members 18, and the lower edges of the latter firmly seated against shoulders formed by the upper sides of the ridges 24,—with the lugs 32 engaged in the recesses 33, 34. The adjacent faces of the shoulders 30, 31 are concave, and the opposite sides of the wedges 35 are correspondingly convex, and the faces of the shoulders 31 are inclined in correspondence with the taper of the wedges, as shown. The wedges 35 may be powerfully forced home and held in place by tightening up nuts 36 on bolts 37 that extend through laterally projecting apertured lugs 38 on the ends of the wedges. The heads 39 of the bolts 37 lie in undercut recesses at the inner ends of grooves in the side members 11, 12 of the box structure 10. The load or weight of the locomotive is freely received by the member 17, independently of the box structure 10, through the opening between the shoulders 30, 30 of the latter. As shown in Fig. 2, the member 17 has recesses 42, 42 in its upper side for receiving corresponding projections on the spring saddle (not shown). The box structure 10, therefore, is entirely unloaded as respects the vehicle weight, but engages the vehicle frame and the member 17, keeps the bearing structure 17, 18 in position, and receives and transmits to the frame the side thrust from the wheel. The members 18 transmit the horizontal "fore and aft" thrust from the journal or shaft 15 to the locomotive frame 14 through the box structure 10 independently of one another, as well as stresses due to the tendency of the bearing to turn with the shaft.

The outer faces 43, 44, 45 of the box structure 10 and the members 17, 18, are flush with one another, and afford bearing surfaces for engaging the driver wheel hub (not shown) and taking the side or "end" thrust from the wheel. Since this bearing surface is on all of the parts 10 and 17, 18, and extends all the way around the shaft 15, it is of greater area than heretofore possible in standard practice, so that the pressure is more widely distributed, and the wear will be more uniform and not so great. The thrust bearing surfaces 43, 44, 45 are kept

accurately in alignment by the engagement of the lugs 32 in the recesses 33, 34 and by the wedges 35. These bearing surfaces 43, 44, 45 may consist of babbitt facings or linings on the parts 10 and 17, 18, as shown.

It will be seen that in order to remove the crown bearing structure from the journal box 10, it is only necessary to relieve the bearing of the spring tension and lift the 10 spring saddle (not shown) out of engagement with its recesses 42, 42; withdraw the wedges 35; and drop the box sufficiently to disengage the members 18 therefrom at 32, 34. Having been disengaged from the box 15 10 by vertical displacement therein as just described, the whole bearing structure may be removed from the box by simply moving the same lengthwise of the axle 15. (Or, by removing the shims 34, it may be possible 20 to drop the members 18 sufficiently to permit their separate removal before or after the member 17.) The entire lubricator or cellar 20 can be removed for repacking or 25 cleaning without disturbing the wedges 35 or the members 17, 18, by simply withdrawing the rod or pin 27. The cellar 20 shown has, of course, an end wall at its "inner" end where the indicator rod 26 is, but is open for cleaning or repacking (without any end 30 wall) at its outer or hub end,—the place of an end wall at this end being taken by the transverse flange or web 46 of the box structure 10 on which is the babbitted bearing face 43. When the box structure 10 is to be 35 removed from the locomotive frame in order that its hub face 43 may be relined (or for any other reason), it is only necessary to remove the bearing structure as just described, drop the frame pedestal binder 47 so as to 40 open the lower ends of the guideways 14, and allow the box structure 10 to slide or drop down from the axle 15,—the opening between the shoulders 30, 30 at the upper end of the box structure being of width sufficient to pass the shaft readily, though of less 45 width than the member 17 as a whole. No drop pit crane is required for removal of any or all the bearing parts, as just described; neither is it necessary to drop the 50 wheels or to lift the locomotive as a whole from its frame for such purposes.

It will be readily appreciated that the provision of some separately movable means (such as the members 35) for holding or wedging the bearing structure fast in the box 10 makes the removal of the bearing considerably easier than if (in the absence of such engagement means as 32, 33, 34) the parts 10 and 17, 18 were themselves adapted 60 to wedge or interlock when the latter were pushed home into position. This is because such separately removable members can be much more readily "broken loose" from the hold of the other parts than a relatively 65 heavy member like the part 17 could be

broken away from the box 10 if the one were directly wedged into the other as in the case supposed. It will also be noted that the load on the bearing does not affect or bear on the holding means 35 in any way 70 that might deform it or interfere with its removal.

Owing to its facility of removal, the member 17 can be made not only a unitary structure but also intrinsically strong and rigid 75 enough to resist any tendency toward crushing together of the box sides 11, 12 at their upper ends,—and, indeed, to maintain itself substantially undeformed under practically any and all stress to which it can ever be 80 subjected in service. Not only can the parts 17, 18 be made quite massive, as shown; but their wearing faces for the axle 15 can be provided with antifriction linings 48 of babbitt or the like that may require frequent 85 renewal, but will reduce wear and avoid cutting of the journal; while the rest of it can be made of bronze, steel, or other metal of ample strength. As shown, this babbitted bearing face 48 of the member 17 has a central longitudinal groove 49, which aids lubrication, and also makes the bearing pressure more uniform and prevents the member 17 from wearing flat as a consequence 90 of its tendency to rock one way or the other on top of the axle 15 when the latter is revolving at high speed. And not only can the box structure 10 be made of any material preferred, but distortion and weakening of 95 the box such as results from the pressing of crown brasses into journal boxes of the old type are entirely avoided.

The removal and replacement of the members 17, 18 can be rendered still more easy by making any or all of them of relatively 100 light metal (preferably of specific gravity not exceeding 7 on the standard scale), so as to minimize its weight and specific gravity as a whole, and the consequent difficulty of handling it. Various aluminum alloys light 110 and strong enough for the purpose (such as duralumin) possess bearing qualities; but in general, nevertheless, I prefer to provide a lining of other homogeneous anti-friction metal for them. As the specific gravity of duralumin is but 2.83 and that of the 115 usual bearing metals about 8.5, a duralumin bearing with anti-friction lining may have an average specific gravity quite unprecedentedly low. Owing to the bearing qualities 120 of duralumin, no harm will result if the anti-friction lining should wear away so as to let the bearing proper come in contact with the steel axle: on the contrary, the bearing will run quite satisfactorily till it can 125 conveniently be relined.

The integral character and mass of the crown bearing member 17 (as distinguished from the inserted brass crown bearing piece of the old journal box construction) makes 130

the heat distribution and dissipation better for my construction. While the causes of the pinching in phenomenon between the legs of the U as observed in standard inverted U shaped boxes are not definitely known, it has been supposed to result (in part, if not entirely) from the expansion of the relatively large mass of metal in the base of the U by the absorption of the heat generated in running; but with my construction, the heat in the bearing is well distributed, and does not really pass to the box at all, so that such a tendency can scarcely exist.

Moreover, the integral transverse member 16 of the box structure effectually prevents pinching or crushing in of the sides 11, 12 at the lower end of the box, and thus entirely obviates binding or crushing stresses on the cellar 20 in any case. The liability of displacement or injury of the lubricator is minimized, owing to its protection from crushing stresses and to its being so definitely secured and kept in place.

In the construction illustrated in Figs. 4 and 5, the separate bearing parts or members 18^a at opposite sides of the axle 15 extend from below its center upward and inward over the axle practically to the middle,—so as to rest on the axle and perform the function of the part 17 in Figs. 1-3 in transmitting the load of the vehicle weight to the axle, besides performing the functions of the parts 18 in Figs. 1-3 in transmitting horizontal thrusts independently of one another. In addition to these members 18^a, the bearing structure here shown comprises an upper part of member 50, which freely receives the load of the vehicle weight and freely transmits it through the box opening at 30, 30, independently of the box structure 10. As shown, this upper member 50 engages and rests on the upper ends of the members 18^a, and maintains them in definite relation to one another without interfering with their independent lateral adjustment relative to the box sides 11, 12. The bearing members 18^a have the lugs 32 at their lower ends, which normally engage in the recesses 34 in the box ridge 24, and prevent undesired endwise displacement of said members (lengthwise of the axle 15); while the keys 35 normally engaged between the box shoulders at 30 and the lateral shoulders 31 on said members 18^a normally prevent such vertical displacement of said members as will permit their removal by endwise displacement, and wedge the members fast in the box structure. Changeable shims or liners 34^x may be interposed between the members 18^a and the box sides 11, 12 as a convenient means of controlling the lateral adjustment of said members 18^a.

If desired, means of interconnection between the box sides 11 and 12 may be provided that will prove an additional safe-

guard in preventing spreading of the box. For this purpose, the upper portion 50 of the bearing structure shown in Figs. 4 and 5 may have vertically undercut dovetail lugs 51 that slidably engage the undercut walls 70 of corresponding dovetail recesses 52 in the shoulders 30. Such a connection affords freedom of vertical movement above the bearing 18^a, 18^a, and hence does not prevent the free transmission of weight load to the latter. Also, the part 50 is separately removable "upward" from the box structure 10, so as not to interfere with dropping the latter from the pedestal jaws in the manner already described in connection with Figs. 1-3. When the box 10 is thus dropped, the part 50 is left free for withdrawal lengthwise of the shaft 15.

The horizontal division of the bearing structure as shown in Figs. 4 and 5 allows the upper portion 50 (which has the recesses 42 and directly engages the spring saddle) to be made of steel, with ample strength, while the lower parts 18^a may be made of light metal,—as already described in connection with Figs. 1-3.

Corresponding parts and features in Figs. 4 and 5 have been marked with the same reference characters as in Figs. 1-3, as a means of dispensing with merely repetitive description.

Attention is directed to the fact that the present application is a companion case to applicant's application No. 548,939, filed coincidentally herewith. Certain of the features of the construction disclosed are broadly claimed in said application No. 548,939, the present case being directed simply to the specific structure pointed out in the following claims.

I claim:

1. A vehicle axle journal box construction comprising a yoke-shaped box open at its upper end, and an axle bearing structure in the box overlying the axle and extending substantially below its center, and receiving and transmitting the load of the vehicle weight independently and exclusively of the box.

2. A vehicle axle journal box construction comprising a yoke-shaped box open at its upper end, for engaging the vehicle frame, and an axle bearing structure in the box overlying the axle and extending substantially below its center; said bearing structure transmitting horizontal thrust to the frame through the box, but receiving the load of the vehicle weight independently and exclusively of the box.

3. A vehicle axle journal box construction comprising a yoke-shaped box open at its upper end, and an axle bearing structure therein comprising separate parts at opposite sides of the axle transmitting horizontal thrusts independently of one another.

4. A vehicle axle journal box construction comprising a yoke-shaped box open at its upper end, an upper bearing member in said box, and separate bearing members at 5 opposite sides of the axle kept from vertical displacement by engagement with said upper bearing member.
5. A vehicle journal box construction comprising a box structure for engaging 10 the vehicle frame; an axle bearing structure in said box structure with separate parts at opposite sides of the axle removable by movement lengthwise thereof, and normally kept from such movement by engagement 15 with the box structure, but displaceable to disengage them and permit their removal as aforesaid; and means for normally preventing such displacement.
6. A vehicle axle journal box construction 20 comprising a box structure for engaging the vehicle frame; a bearing structure for engaging the axle and said box structure receiving the load of the vehicle weight independently of the latter, and comprising 25 separate parts at opposite sides of the axle removable by movement lengthwise of the axle after vertical displacement in the box structure; and means for normally preventing such displacement.
7. A vehicle axle journal box construction 30 comprising an erect, uninverted yoke-shaped box, of internal width sufficient to pass the axle and thus bodily removable by dropping past the latter, and a bearing structure for engaging the axle and said box comprising 35 separate parts at opposite sides of the axle.
8. A vehicle axle journal box construction 40 comprising a bearing structure resting on the axle, with separate parts at opposite sides thereof transmitting horizontal thrusts independently of one another, and an erect
- uninverted yoke-shaped box, of internal width sufficient to pass the axle and thus bodily removable by dropping past the latter, suspended from said bearing structure at its own open upper end. 45
9. A vehicle axle journal box construction comprising a box structure with a laterally shouldered opening at its upper end of width sufficient to pass the axle; a laterally shouldered axle bearing structure in said box structure comprising separate parts at opposite sides of the axle; and means interposed between the aforesaid shoulders of box and bearing structures for wedging the 50 latter fast in said box structure.
10. A vehicle journal box construction comprising a yoke-shaped box having an opening in its upper end of width sufficient to pass the axle, and thus bodily removable 55 by dropping past the axle; separate bearing members at opposite sides of the axle; and an upper bearing member in the box resting on the axle. 60
11. A vehicle journal box construction 65 comprising a box; separate bearing members at opposite sides of the axle; and an upper bearing member on the axle cooperating with said first-mentioned bearing members to keep them in the box.
12. A vehicle journal box construction 70 comprising a box; an upper axle bearing member in said box removable therefrom by movement lengthwise of the axle; and separate bearing members at opposite sides of the axle, for transmitting horizontal thrusts, normally cooperating with said upper bearing member to prevent removal thereof as aforesaid. 75

In testimony whereof I have hereunto signed my name.

HARRY S. VINCENT.
